DRIVING SPUR FOR GOLF CLUBS

Filed May 22, 1930

FIG. 4.

WILLIAM J. CONNELL

By *Francis Keiper*
Attorney

Inventor

UNITED STATES PATENT OFFICE

WILLIAM J. CONNELL, OF ROCHESTER, NEW YORK

DRIVING SPUR FOR GOLF CLUBS

Application filed May 22, 1930. Serial No. 454,666.

The object of this invention is to provide a new attachment for golf sticks or clubs which enables the player to hold the club more firmly and accurately while striking the ball so that he can hit the ball more accurately and with greater driving power.

This and other objects of the invention will be illustrated in the drawings, described in the specification and pointed out in the 10 claims at the end thereof.

In the drawings:

Figure 1 is a perspective view of a portion of the handle of a golf club provided with my improved attachment with the right hand 15 of the player shown grasping the club.

Figure 2 is a side elevation of a portion of the handle of the club equipped with my improved attachment.

Figure 3 is a sectional view of the handle 20 of the golf club taken on the line 3x, 3x of Figure 2.

Figure 4 is a side elevation of a portion of the handle of the club equipped with my improved attachment and viewed from the rear 25 of Figure 2.

Figure 5 is a side elevation of a portion of the handle of the golf club viewed from the left of Figure 2.

In the drawings like reference numerals indicate like parts.

In the drawings reference numeral 1 indicates the handle of the golf club and 2 indicates the attachment or driving spur which embodies my invention. This attachment has a seat 3 therein which is semi-cylindrical, or is somewhat more than semi-cylindrical in that it engages half way around, or a little more than half way around the handle of the golf club.

40 This attachment is placed on the golf stick at its thinnest part and is moved endwise along the stick to the thick part of the stick where the seat of the attachment firmly engages with the stick and holds it in place. 45 The attachment is provided with screw holes through which screws or rivets 4 and 5 extend by which it is firmly attached to the handle of the golf club.

50 This attachment is preferably made of metal and is made to fit on the handle of the

golf club and to become integral therewith. It is also made to give the thumb and forefinger a better grip on the handle of the club than would be possible without it so as to increase the bearing which the lower hand has on the club. For this purpose one side of the attachment is provided with a spur 9 on one side of which is a flat side wall 6 which is approximately tangential with the handle of the club. Extending diagonally or spirally across the attachment is a groove 7 on one side of which is the tapering wall 8, which rises to the peak of the spur 9, and then tapers off again radially and ends in an elevation or projection 10. On the other side of the groove 7 is provided an elevation 11 between which elevation 11 and the spur 9, the groove 7 is located.

As shown in Figure 1, the player's hand grasps the handle of the club and the thumb normally rests in the groove 7 with the edge of the palm and a part of the forefinger resting against the tangential wall 6 with the spur between them. The end of the forefinger engages in the hollow portion 12 between the elevation 11 and 10. Between the thumb and the palm, the club is grasped with a leverage due to the projection of the spur 9 indicated at Figure 5, which enables the player to hold the club just that much more firmly so that the club and its head is always held correctly in position for the stroke, and so that at the time of impact with the ball the head of the club cannot turn sideways and foul the stroke and drive the ball incorrectly, but instead the head of the club will keep its correct position and communicate the full energy of the stroke to the ball thus securing accurate driving for the longest possible shot.

I claim:

1. An attachment for the handle of a golf stick comprising a seat that is adapted to surround more than half the handle of the golf stick, a spur on said attachment having one side thereof extending along the handle and substantially tangential to the handle, a groove extending diagonally or spirally around the attachment on the other side of said spur.
2. An attachment for the handle of a golf

- stick comprising a seat that is adapted to surround more than half the handle of a golf stick, a spur on said attachment having one side thereof substantially flat and extending along the handle, a groove extending diagonally or spirally around the attachment on the other side of said spur.
3. An attachment for the handle of a golf stick comprising a seat that is adapted to surround more than half the handle of a golf stick, a spur on said attachment having one side thereof substantially flat and extending along the handle, a groove extending diagonally or spirally around the attachment on the other side of said spur, projections on the other side of said attachment one at each end thereof, said groove terminating between said projections.
4. An attachment for the handle of a golf stick comprising a seat that is adapted to surround more than half the handle of a golf stick, a spur on said attachment having one side thereof substantially flat and extending along the handle, the other side of said spur being tapered longitudinally and beveled transversely.
5. An attachment for the handle of a golf stick comprising a seat that is adapted to surround more than half the handle of a golf stick, a spur on said attachment having one side thereof substantially flat and extending along the handle, the other side of said spur being tapered longitudinally and beveled transversely, a groove extending diagonally or spirally around the attachment on the beveled side of the spur.

In testimony whereof I affix my signature.
WILLIAM J. CONNELL.
